PRESSURE CASTING MACHINE LINK
MECHANISMNathan Lester, Cleveland, Ohio, assignor to The
Lester Engineering Company, Cleveland, Ohio,
a corporation of Ohio

Application October 4, 1939, Serial No. 297,916

3 Claims. (Cl. 22—92)

The present invention relates to a new and improved mechanism for imparting opening and closing movement to the die plates of a pressure casting machine. In such a machine, the die plates carry the mold members or die blocks in which the mold cavity is formed when such die plates are in closed position, and into which cavity the material to be cast is forced under extremely high pressure. The die plates must, therefore, be held in closed position under a relatively great force or pressure which is sufficient to withstand the casting pressure tending to open them.

Toggle link mechanism has heretofore been employed as a means for securing the relatively high pressure or force required for moving and holding the die plates of the pressure casting machine to closed position. The die plates are moved to open position in order to permit ejection of the resultant casting. Where both relatively deep or elongated castings are to be made, as well as where it is desired to have an increased working space between the die plates, the amount of movement heretofore obtainable through toggle link mechanism has been found to be necessarily limited.

On the other hand, where large opening and closing movement between the die plates has been desired, the toggle link mechanism has been eliminated and the die plates moved by direct connection to a hydraulic ram. However, in order to secure adequate die-closing pressure, the latter type of device must be made extremely large and cumbersome, as well as requiring much more extensive and expensive auxiliary apparatus in the way of pressure pumps, supply lines and pressure fluid reservoirs.

It is the general object and nature of my present invention to provide mechanism for imparting opening and closing movement to the die plates of a pressure casting machine, which comprises a novel combination of both a toggle link mechanism and a hydraulic ram. In other words, my invention retains and combines the advantageous features of the relatively high mechanical advantage produced by the toggle link mechanism, together with the relatively increased amount of die plate movement produced from a hydraulic ram.

A further object and advantage of my invention is that the toggle link mechanism is operated only during a fractional portion of the relative movement or traverse of the die plates and hence, the mechanical advantage incident to the use of such a toggle link mechanism is utilized

only during the very portion of die plate movement wherein it is best suited and desired. For the remainder of the movement of the die plate, the toggle link mechanism moves bodily with the prime moving element, i. e., the hydraulic piston, so that the movement of the latter is transmitted directly to the movement of the die plate.

Additional objects and advantages of my invention shall become apparent as the following description proceeds.

To the accomplishment of the foregoing and related ends, said invention, then consists of the means hereinafter fully described and particularly pointed out in the claims.

10 The annexed drawing and the following description set forth in detail certain mechanism embodying the invention, such disclosed means constituting, however, but one of various mechanical forms in which the principle of the invention may be used.

In said annexed drawings:

Fig. 1 is a longitudinal, vertical sectional view taken through that portion of a pressure casting machine to which the present invention relates, and showing the die plate and its attached moving mechanism in closed position; Fig. 2 is a view similar to Fig. 1 but showing the parts in partially opened position; Fig. 3 is another view similar to Figs. 1 and 2, but showing the parts in fully open position; and Fig. 4 is a horizontal, sectional view taken substantially along line 4—4 of Fig. 2.

Now referring more particularly to the drawings, there is shown therein the bed-plate or base frame 1 of a pressure casting machine upon which the horizontal tie beam 2 is mounted in spaced relationship and by means of the vertical, stationary end plate 3 and the end framework 4. The fixed die plate 5 is mounted between the base frame 1 and beam 2. The movable die plate 6 is adapted to move back and forth in the space between the base 1 and beam 2, being guided upon tie bars, such as indicated at 7. The frame members 1, 2, 3 and 4 thus constitute a fixed frame structure in which the die plate 5 is stationarily mounted and in which the die plate 6 is movably mounted.

The die plates 5 and 6 are adapted to support die blocks, such as indicated at 8 and 9, respectively, and in which the mold cavity is formed. A screw jack 10 adjustably mounts the die plate 6 with respect to its carriage plate 11, in order to provide for preliminary adjustments in the space between the die plates 5 and 6.

55 A pair of links 12 are pivotally connected by

means of the pivot pins 13 to the rear or left-hand face of the carriage plate 11. The links 12, in turn, are pivotally connected by means of the pivot pins 14 to the second pair of links 15, and the latter are pivotally connected by means of the pins 16 to the end of the piston rod 17.

The piston rod 17 carries the piston 18 which reciprocates within the fixed hydraulic cylinder 19 mounted on the end of the frame member 4.

The forward or righthand end of the links 12 have arcuate bosses or segments 20 which are adapted to fit complementary, arcuate bearing surfaces on the carriage plate 11. Hardened metal inserts 21 and 22 are mounted in the last-named arcuate bearing surfaces respectively, and are adapted to be in alignment and bear against each other when the links 12 are in closed position, such as shown in Fig. 1.

Abutments or shoulders are provided upon the links 12 at points closely adjacent the pivot pins 14. These abutments are in the form of hardened metal inserts 23 which are adapted to bear against other hardened metal abutments 24 carried in the frame member 4. The abutting surfaces of the members 23 and 24 are inclined at an acute angle, as indicated by the line *a*, to the normal to the direction of traverse of the die plate 6, and thus, constitute wedges or wedge surfaces, which, when slid one over the other, will impart a wedging action to the longitudinal movement of the links 12 and its connected plates 11 and 8.

Slide-ways or slide bearing surfaces 26 are mounted in the frame member 4 adjacent the abutments 24 and disposed in a position parallel to the direction of movement of the die plate 6 and of the piston rod 17. These bearing surfaces 26 are adapted to make sliding engagement with bearing surfaces 27 on the intermediate portion of the links 12.

Laterally projecting legs 28 extend inwardly from the sides of the links 12 and are adapted to contact each other in end-abutting relationship and to thus limit the collapsing movement of the links 12 and 15. Referring to Figs. 1 and 2, it will be seen that the links 12 have a pivotal movement from the two extremes shown in the respective figures. This amount of pivotal movement is exemplified by the longitudinal center lines *b* and *c*, respectively, shown in Fig. 2. The distance *d* represents the chord of the arc of pivotal movement of the links 12 at the surface of the abutment 23. The righthand end of the links 12 is offset laterally so that the center of the pivot pin 13 is correspondingly offset a distance *d* from the center line *b* of the links 12. Thus, the links 12 are adapted to occupy a position at the inward extreme of their pivotal movement, where their longitudinal bearing surfaces will be parallel to the direction of traverse of the die plate 6 and adapted to make surface to surface contact with the bearing surfaces 26.

From the foregoing description, the operation of the mechanism should now be apparent.

Commencing with the position of the parts as shown in Fig. 3, the piston rod 17 is moved in a righthand direction which corresponds to closing movement of the die plate 6. Since the bearing surfaces 27 of the links 12 are in contact with the bearing surfaces 26 on the frame member 4, they cannot move outwardly but will slide along longitudinally until the parts approach closed position of the die plates, as shown in Fig. 2. At this point, the links 12 are freed for outward pivotal movement and the free pivots 14

also undergo pivotal movement whereby a toggle action is effected to force the wedge surface abutments 23 and 24 in contact, and thereby, to press the die plates 5 and 8 with their respective die blocks 8 and 9 into tightly closed relationship, as shown in Fig. 1.

Upon return or opening movement of the die plates, the piston rod 17 is moved in a lefthand direction, which, in turn, operates to effect a collapsing movement of the toggle links 12 and 15 until the projecting legs 28 abut against each other and thereby limit such movement. At this point, the links 12 will then be in a position so that the abutment 23 clears the abutment 24 and the links 12 and 15 will then be in a rigid position, with their pivotal movement immobilized so that they will move bodily along with the piston rod and the plates 11 and 8 to produce a quick-acting opening movement of die plates.

The links 12 and 15 are thus joined in a pivot, at the pin 14, which is non-connected to any other link mechanism element which might determine its path of travel; such pivot, therefore, being a free pivot, the movement of which is controlled indirectly by the movement permitted to the links 12. It will also be noted that the maximum mechanical advantage incident to toggle link action is obtained when the links 15 reach a position of longitudinal alignment, i. e., when the centers of the pins 14 and 16 are in a straight line. Thus, the toggle link mechanism approaches and reaches "dead center" position as the wedge surfaces of the abutments 23 and 24 are in contact.

The superior mechanical advantage obtained through the combined action of the toggle link mechanism and of the wedge surfaces of the abutments 23 and 24 is operative only during that portion of the stroke of the die plate movement where it is most suited and required. Such portion of the stroke is indicated by the distance *e* in Fig. 1. The remainder of the opening and closing stroke or movement of the die plate 6 is produced directly by movement of the piston rod 17.

In this manner, relatively rapid opening and closing movement of the die plates, as well as a relatively large amount of such movement is obtained. At the same time, the very high force or pressure required for holding the die plates in closed position is not sacrificed.

Other modes of applying the principle of my invention may be employed instead of the one explained, change being made as regards the mechanism herein disclosed, provided the means stated by any of the following claims or the equivalent of such stated means may be employed.

I, therefore, particularly point out and distinctly claim as my invention:

1. A pressure casting machine link mechanism comprising a fixed frame member, a die plate movable thereon, a pressure cylinder, piston and piston rod so mounted on said frame member as to move said piston rod in a direction parallel to that of said die plate, dual link members each pivotally connected at one end to said die plate, other dual link members each pivotally pinned at one end to said piston rod, the other ends of each of said dual link members being connected to each other at a free pivot, and complementary straight, angular wedge surfaces on said first-named dual link members and on said frame member respectively, said wedge surfaces being

adapted to contact each other and to impart wedge action movement to said die plate during movement of said free pivot, said wedge surfaces on said link members forming a bodily part thereof, said other dual link members being in alinement when said complementary wedge surfaces are fully engaged.

2. A pressure casting machine link mechanism comprising a fixed frame member, a die plate movable thereon, a pressure cylinder, piston and piston rod so mounted on said frame member as to move said piston rod in a direction parallel to that of said die plate, dual link members each pivotally connected at one end to said die plate, other dual link members each pivotally pinned at one end to said piston rod, the other ends of each of said dual link members being connected to each other at a free pivot, complementary straight, angular wedge surfaces on said first-named dual link members and on said frame member respectively, said wedge surfaces being adapted to contact each other and to impart wedge action movement to said die plate during movement of said free pivot, and laterally extending projections on each of said first-named dual link members, said projections being adapted to abut each other when said wedge surfaces are moved out of contact, said other dual link members being in alinement when said complementary wedge surfaces are fully engaged.

3. A pressure casting machine link mechanism

comprising a fixed frame member, a die plate movable thereon, a pressure cylinder, piston and piston rod so mounted on said frame member as to move said piston rod in a direction parallel to that of said die plate, dual link members each pivotally connected at one end to said die plate, other dual link members each pivotally pinned at one end to said piston rod, the other ends of each of said dual link members being connected to each other at a free pivot, complementary straight, angular wedge surfaces on said first-named dual link members and on said frame member respectively, said wedge surfaces being adapted to contact each other and to impart wedge action movement to said die plate during movement of said free pivot, laterally extending projections on each of said first-named dual link members, said projections being adapted to abut each other when said wedge surfaces are moved out of contact, and slide bearing surfaces on said frame member parallel to said piston rod and adapted to contact with each of said first-named dual link members during longitudinal pivotal movement of the latter, said bearing surfaces terminating at said wedge surfaces on said frame member whereby said dual link members are freed for pivotal movement towards contacting engagement of said wedge surfaces, said other dual link members being in alinement when said complementary wedge surfaces are fully engaged.

NATHAN LESTER.
